TAP STARTER

Grosvenor M. Cross, Brookline, Mass.

Application April 29, 1935, Serial No. 18,850

4 Claims. (Cl. 10—147)

This invention relates to a device for guiding and insuring the correct position of a screw thread cutting tap or similar tool when starting its operation in a previously formed hole. Such a tap must be held in accurate alignment with the hole in the work because if the tap is started in an angular direction it will bind, cut the thread imperfectly, and if, after it is started in the work, it be forced back into aligned position, it may be damaged or broken and the work injured.

The object of the present invention is to provide a simple construction which will surely and accurately guide the tap or similar tool in the starting of the work, maintaining it in aligned position with the hole in the work.

The object of the invention is to provide such a device which shall be of a universal character, sturdy, practically indestructible, having no movable parts to get out of order, inexpensive in construction, capable of use with a large range of tap sizes, and capable of use upon work presenting either a flat surface or a curved or angular surface.

These and other objects and features of the invention will appear more fully from the accompanying description and drawing and will be particularly pointed out in the claims.

The drawing illustrates preferred forms of construction embodying the invention in which:

Fig. 1 is a top plan view of one form of such construction.

Fig. 2 is a bottom plan view of the construction shown in Fig. 1.

Fig. 3 is a side elevation of the construction shown in Fig. 1.

Fig. 4 is a cross section taken on the line 4—4 of Fig. 1.

Fig. 5 is an end elevation of another form.

Fig. 6 is a plan view of the construction shown in Fig. 5.

A device embodying the invention is in the form of a block made of any suitable, rigid, hard material. The construction is such that the entire device may be made, for example, of metal by a die casting operation and may be desirably finished with chromium plating.

The block of this invention may be of various shapes, the simplest and preferred examples of which are illustrated. The essential features of the broad construction are that it must present positioning means to rest upon and position it with respect to a flat work-piece, that it must present a plurality of rectilinear V-shaped positioning grooves extending across the block in which cylindrical work-pieces may be seated and

thus the block be positioned with respect to the axes of such cylindrical work-pieces, that there shall be a plurality of tap-guiding cylindrical bores extending through the block each with its axis normal to, and intersecting the apex of, and bisecting the angle of, one of the V-shaped grooves and with the diameters of the bores corresponding respectively to the diameters of a plurality of taps, so that the axis of each bore will be normal to the flat surface of a work-piece positioned by the block and normal to the axis of a cylindrical work-piece positioned by a groove, and that the block shall be of sufficient depth or thickness properly to support the taps as they are guided into the work-piece.

In the construction illustrated in Figs. 1 to 4, the block is of flat cylindrical shape presenting the flat bottom positioning surface 1. Three rectilinear V-shaped symmetrical positioning grooves, that is, grooves each of which has its two faces of equal and uniform depth throughout, 2, 3, and 4 extend, in this case transversely and diametrically, across the block and upward from the bottom surface. The block is preferably lightened in weight and the material thereof reduced by a central depression 5 at the top, a central depression 6 at the bottom and by symmetrical V-shaped recesses 7 extending downward from the top and inward from the sides leaving at the top of the block the ribs 8 above the V-shaped positioning grooves.

The flat bottom positioning surface is defined by the edges of the V-shaped grooves and, while the bottom depression 6 and the V-shaped grooves themselves remove a large portion of the bottom surface, extensive sections are left so that the block when placed upon the flat surface is accurately positioned thereon by this surface of which the edges of the grooves are elements.

When the block is to be used with cylindrical work-pieces such as rods or bars, it is placed with one of the transverse V-shaped grooves resting over the rod or bar and thus again the block is accurately positioned and supported with respect to the surface of the rod or bar.

It will now be seen that a large number of tap guiding bores may be formed in the block each one of which can have the same relation to the flat work-piece positioning element and to one of the grooves thus enabling a wide range of tap sizes to be guided by the use of a single block embodying the invention. These cylindrical bores are formed in the block and extend entirely therethrough each with its axis normal to the bottom positioning surface 1 or the surface 55

defined by the groove edges and each with its axis intersecting the apex of one of the V-shaped grooves. In the construction illustrated the block is formed to be used for guiding screw thread cutting taps for A. S. M. E. standard machine screw sizes 2, 3, 4, 5, 6, 8, 10, 12, $\frac{1}{4}$ ", $\frac{5}{16}$ ", but it is obvious that the number of sizes and the particular diameters may be varied as required. In the present construction the large size, $\frac{5}{16}$ ", is at the center of the block while the other sizes are distributed in the ribs 8. In the case of the larger sizes the cylindrical bores such as 9 are of the same size throughout the block, while in the case of the smaller sizes such as 2, 3, 4 and 5, where the shank of the tap is usually of larger diameter than the thread cutting portion, these bores are formed as shown at 10 with the upper portion of a diameter fitting the shank and the lower portion of a diameter fitting the thread cutting portion of the tap.

It will thus be seen that when it is desired to start a tap of any of the many sizes provided for in such a block in a hole in a piece of work whether the work be flat or of other shape, the block is positioned on the work with its flat bottom positioning surface engaging the surface of the work, if the work be flat, or with the proper V-shaped groove engaging the work, if the work be a rod or bar, for example, and in each case the proper cylindrical bore is readily held in accurate alignment with the axis of the hole in the work. The tap is then inserted in the bore and its correct position insured while being operated until it has well started in the work when it and the block may be removed and the operation completed.

The same principles are embodied in the constructions shown in Figs. 5 and 6. In this form the block is of a general polygonal shape and the V-shaped positioning grooves 11, 12 and 13 extend longitudinally of the block inward from the sides of the block. Each of these positioning grooves having its two faces of equal and uniform depth throughout therefore presents parallel edges 14 for the groove 11, 15 for the groove 12, and 16 for the groove 13, adapted to rest upon and position the flat surface of a work-piece while a cylindrical work-piece may be seated in and positioned by each groove. The parallel edges of the grooves are preferably extended into plane surfaces such as 20 normal to the axes of the bores thus to give a wider seat for the block on the flat surface of the work-piece. The block is preferably reduced by the V-shaped grooves 17, 18 and 19 to render the block symmetrical and lighten the construction. The plurality of cylindrical bores of the type already described for guiding the taps of the different sizes are shown with the corresponding tap sizes. Each of these cylindrical bores extends through the block and has its axis normal to, and intersecting the apex of, and bisecting the angle of, one of the V-shaped grooves 11, 12 or 13.

Thus it will be seen that this construction shown in Figs. 5 and 6, when positioned either upon the flat surface of a work-piece or upon a cylindrical work-piece, ensures the accurate starting of either size of tap into the work.

The block may also be used for guiding a drill in drilling a hole such, for example, as is subsequently to be tapped and for this purpose one of

the bores of a smaller size than the tap may be employed or separate bores may be formed in the block for that purpose.

There is thus presented a very simple, inexpensive, efficient device of a universal character capable of handling a wide range of sizes of taps or similar tools and ensuring the accurate location and starting of the tap in work of various characters.

Having thus described the invention, what is claimed as new, and desired to be secured by Letters Patent, is:

1. A tap starter comprising a rigid, hard block having a plurality of rectilinear V-shaped positioning grooves extending across the block with the two faces of each groove of equal and uniform depth throughout and a plurality of cylindrical bores of different diameters extending through the block, each with its axis normal to, intersecting the apex of, and bisecting the angle of, one of the V-shaped grooves and with the diameters of the bores corresponding respectively to the diameters of a plurality of taps of different sizes to cause the axis of each bore to be normal to the flat surface of a work-piece positioned by the edges of its groove and normal to the axis of a cylindrical work-piece seated in and positioned by its groove.

2. A tap starter comprising a rigid, hard, polygonal block having a plurality of parallel V-shaped positioning grooves extending longitudinally of the block and inward from the sides of the block with the two faces of each groove of equal and uniform depth throughout and a plurality of cylindrical bores of different diameters extending through the block, each with its axis normal to, intersecting the apex of, and bisecting the angle of, one of the V-shaped grooves and with the diameters of the bores corresponding respectively to the diameters of a plurality of taps of different sizes to cause the axis of each bore to be normal to the flat surface of a work-piece positioned by the edges of its groove and normal to the axis of a cylindrical work-piece seated in and positioned by its groove.

3. A tap starter comprising a rigid, hard block having a flat bottom positioning surface, a plurality of V-shaped symmetrical positioning grooves extending transversely across the block and upward from the bottom positioning surface, and a plurality of cylindrical bores of different diameters extending through the block, each with its axis normal to the bottom positioning surface and intersecting the apex of one of the V-shaped grooves and with the diameters of the bores corresponding respectively to the diameters of a plurality of taps of different sizes.

4. A tap starter comprising a rigid, hard, cylindrical block having a flat bottom positioning surface, a plurality of diametrically disposed V-shaped symmetrical positioning grooves extending upward from the bottom positioning surface, and a plurality of cylindrical bores of different diameters extending through the block, each with its axis normal to the bottom positioning surface and intersecting the apex of one of the V-shaped grooves and with the diameters of the bores corresponding respectively to the diameters of a plurality of taps of different sizes.
